UNITED STATES PATENT OFFICE.

ALFRED LEISTMANN, OF BROOKLYN, NEW YORK.

GAS-HEATER.

1,346,456.

Specification of Letters Patent. Patented July 13, 1920.

Application filed March 2, 1920. Serial No. 362,695.

To all whom it may concern:

Be it known that I, ALFRED LEISTMANN, a citizen of the United States, residing at Brooklyn, in the county of Kings and State 5 of New York, have invented a new and useful Gas-Heater, of which the following is a specification.

This invention relates to new and useful improvements in heating stoves, and more 10 particularly to portable stoves of this character especially adapted for burning gaseous fuel.

The primary object of the invention is to provide a heating stove having means to 15 increase the heating surface thereof, thus insuring the maximum amount of heat from a given quantity of fuel.

A further object of the invention is to provide a stove wherein the elements thereof 20 may be readily and easily removed and replaced, in the event that it becomes necessary to repair or clean the same.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, may be made within the scope of what is claimed, without departing from the spirit of the invention.

Referring to the drawings:

Figure 1 illustrates a longitudinal sectional view through a stove constructed in accordance with the present invention.

Fig. 2 illustrates a plan view, the upper plate of the stove being shown as partly broken away, and

Fig. 3 illustrates a fragmental detail view of the mixing chamber of the burner.

Referring to the drawings in detail, the reference character 1 designates the outer casing of the stove, the same being preferably circular in cross section, but it is to be understood that the design of the stove may be changed to meet various requirements of use.

A supporting collar 2, provides the support for the outer casing 1, the flange formed adjacent the lower end of the collar 2, and indicated by reference character 3 forming an abutment for the lower extremity of the lower casing 1.

55 This supporting collar 2 embraces a portion of each of the supporting legs 4, ad-

jacent the upper extremity thereof, and as shown the supporting collar 2 is provided with openings disposed in registry with suitable openings formed in the legs 4, which 60 openings are also in registry with openings formed in the outer casing 1, to accommodate the bolts 5, whereby the outer section 1, collar 2, and legs 4 may be rigidly secured together.

Extending inwardly from the legs 4 are the lugs 6, which lugs provide supports for the protecting plate 7, which is formed of suitable heat resisting material, and adapted to protect the surface on which the stove is 70 supported from the heat radiating from the stove proper.

Having connection with the inner side wall of the legs 4, adjacent the upper end thereof, is a tubular inner casing 8 which is 75 secured to the legs 4 by means of the bolts 5, the bolts 9 being also provided for securing the inner section 8 in proper spaced relation with the outer casing 1, thus providing an annular heat passageway 10.

Formed integral with the outer casing 1, is a relatively flat top 11 provided with a series of openings 12 disposed in suitable spaced relation with each other adjacent the periphery of the outer casing 1, the openings being, however provided directly over the annular heat passageway 10 to permit the heat radiating from the inner section 8 to pass upwardly through the openings 12.

An opening 13 is formed in the stove top 90 11, substantially centrally thereof, and accommodates the upper extremity of the burner supporting rod 14, the upper end of said rod being threaded to receive the knob 15, the lower end of which is adapted to contact with the upper surface of the top 11 to support the rod 14 in proper relation with the inner walls of the inner section 8.

As shown, the lower end of the rod 14 is 95 threaded to coöperate with suitable threads formed on the wall of the opening 16 of the burner 17, whereby the burner may be secured to the rod 14.

Embracing the rod 14, are a plurality of spacing collars 18 that are disposed throughout the length of the rod, which collars are provided for supporting the baffle plates 19, in suitable spaced relation with each other, the baffle plates being shown as clamped between adjacent collars. Openings 20 are 110 formed in each of the baffle plates 19 and disposed in a manner so that the openings of

one plate lie directly under the openings of the adjacent plate to permit the heat to pass upwardly through the openings.

The burner may be of any predetermined configuration but as shown, the same comprises a plurality of arms 21 having the upper surfaces thereof apertured as at 22 to permit the gas entering the burner proper to pass outwardly therethrough. Supported adjacent the lower end of the stove proper is a mixing chamber comprising the inner pipe 23 having threaded connection with the burner, as at 24, the pipe 23 being provided with an elongated opening 25 formed in the upper surface thereof, which opening is adapted to register with the opening 26 formed in the adjustable sleeve 27, whereby the amount of air entering the mixing chamber may be regulated according to the supply of fuel passing therethrough.

Secured to the opposite end of the pipe 23 is the thimble 28 having a reduced portion 29 provided with internal threads to accommodate the threads of the connecting pipe 30, the discharge nozzle 31 being removably supported within one end of the pipe 30 and having its discharge end terminating at a point adjacent one end of the elongated opening 25, so that the air entering the mixing chamber, directly contacts with the fuel from the discharge nozzle.

A finishing ring 32 is supported by top 11 and is provided with a downwardly curved flange 33 which ring is adapted to partially cover the openings 12 to increase the draft through the openings.

In the operation of the device it is of course apparent that a suitable valve is employed for controlling the supply of gaseous fuel, to the burner proper, which valve is opened to permit a predetermined quantity of fuel to pass into the burner. The burner is lighted with the result that the heat generated by the burner passes upwardly contacting with the baffle plates to heat the same, thereby increasing the heating surface of the stove.

Having thus described the invention, what I claim as new is:—

50 1. A heater including supporting legs, an

outer cylindrical casing having connection with the supporting legs, an inner casing having connection with the supporting legs and disposed in spaced relation with the outer casing, a cover, said cover having a plurality of openings formed therein, a supporting rod having one extremity disposed in one of the openings of the cover, a burner having threaded connection with one end of the supporting rod, a plurality of baffle plates supported on the supporting rod, and collars for securing the baffle plates in spaced relation with each other.

2. A heater including supporting legs, an outer and inner casing having connection with the supporting legs, said casings being supported in spaced relation with each other to provide a heat passageway, a cover for the casings, a supporting rod having one extremity removably connected to the cover, a plurality of spaced baffle plates supported by the supporting rod, a burner carried by one end of the supporting rod, and means for feeding fuel to the burner.

3. A heater including supporting legs, an outer and an inner casing having connection with the supporting legs, said casings being disposed in spaced relation with each other, a cover for the casings, said cover having a central opening, a supporting rod having one extremity threaded and extending through the opening, a knob positioned on the upper end of the supporting rod for securing the rod to the cover, the lower end of said supporting rod terminating at a point adjacent the lower end of the casings, a burner having threaded connection with the lower end of the supporting rod, a plurality of spaced baffle plates disposed on the supporting rod, and a collar positioned between each of the baffle plates, and means for supplying fuel to the burner.

In testimony that I claim the foregoing as my own I have hereto affixed my signature in the presence of two witnesses.

ALFRED LEISTMANN.
